United States Patent

Des. 240,447
Patented July 6, 1976

240,447

PLANTER

Marshall D. Le Vine, 8359 Colesville Road,
Silver Spring, Md. 20910

Filed June 11, 1975, Ser. No. 585,783

Term of patent 14 years

Int. Cl. D11—02; D23—01

U.S. Cl. D35—3 B

FIG. 1.

FIG. 2.

FIG. 3.

FIG. 4.

FIG. 5.

FIG. 1 is a perspective view of a planter showing my new design;

FIG. 2 is a side elevational thereof;

FIG. 3 is a top plan view thereof;

FIG. 4 is a perspective view of a modified embodiment of the planter illustrated in FIG. 1; and

FIG. 5 is a further modified embodiment of the planter illustrated in FIG. 1.

I claim:

The ornamental design for a planter, substantially as shown and described.
